UNITED STATES PATENT OFFICE.

MANUEL A. T. GILLBEE, OF PHILADELPHIA, PENNSYLVANIA.

DESIGN FOR A PICTURE FRAME OR MOUNT.

SPECIFICATION forming part of Design No. 28,807, dated June 7, 1898.

Application filed December 17, 1896. Serial No. 616,073. Term of patent 7 years.

To all whom it may concern:

Be it known that I, MANUEL A. T. GILLBEE, a citizen of the United States, residing in Philadelphia, Pennsylvania, have invented a certain new and original Design for a Picture Frame or Mount, of which the following is a specification.

My design for a picture frame or mount is fully shown in the accompanying drawing, which represents a front view of the same.

My design consists, essentially, of the shape or configuration of the beveled outer edges of the frame or mount. The opposite side edges *a a* are straight, and the bottom edge *b* is also straight, the lower corners *d d* being rounded. The top has rounded corners *f f*

and a central raised and rounded portion *g*, between which and the rounded upper corners *ff* are concave portions *i i*, merging into the rounded central portion *g* and rounded corners. 20

I claim—

The design for a picture frame or mount, substantially as described and as shown in the accompanying drawing. 25

In testimony whereof I have signed my name to this specification in the presence of two subscribing witnesses.

MANUEL A. T. GILLBEE.
